UNITED STATES PATENT OFFICE

CLIFFORD J. CHAMBERLAND, OF LEWISTON, MAINE

TRAFFIC SIGNAL

Application filed May 4, 1927. Serial No. 188,813.

This invention relates to signals and more particularly to a signal intended to be used by a traffic officer in order to direct traffic across a street intersection.

5 One object of the invention is to provide a signal which may be worn upon the hand and illuminated so that an officer may direct traffic by hand motions and the driver of an automobile easily see the signal at night.

10 Another object of the invention is to permit the officer to carry a stop and a go signal upon the same hand and selectively display the signals to the driver of an automobile so that the officer may easily indicate to a

15 certain automobile driver the direction in which he wishes him to move.

Another object of the invention is to provide improved means for securing signals one against the front or palm and the other 20 against the back of a hand and to so form the means for carrying the signals that it may be comfortably worn upon a hand and easily applied thereto or removed.

Another object of the invention is to provide the signals with legends which are pivotally mounted and weighted so that when the officer moves his hand the legend will remain in such position that it may be easily read by the driver of an automobile.

25 Another object of the invention is to protect the legend from damage but at the same time permit it to be easily seen by the driver of an automobile when the signal is illuminated and to also permit a colored light to be displayed which together with the legend will accurately indicate the wishes of the traffic officer to the driver of an automobile.

Another object of the invention is to permit the signals at the front and back of the 40 hand to be both illuminated by electric current flowing from a battery carried upon the person of the traffic policeman.

The invention is illustrated in the accompanying drawings, wherein:

45 Figure 1 is a perspective view showing the improved signal in use by a traffic officer;

Fig. 2 is an enlarged front elevation of one of the signals;

50 Fig. 3 is a vertical sectional view taken on the line 3—3 of Fig. 4;

Fig. 4 is a vertical sectional view taken on the line 4—4 of Fig. 2;

Fig. 4^a is a fragmentary view of the upper portion of Fig. 4;

Fig. 5 is a perspective view of the battery receptacle with a battery disposed therein and the cover of the receptacle swung to an open position;

Fig. 6 is a view of the means for carrying the two signals;

Fig. 7 is a sectional view taken on the line 7—7 of Fig. 6;

Fig. 8 is a view similar to Fig. 2 showing the second signal forming part of the device;

Fig. 9 is a wiring diagram.

The improved traffic signal includes a carrier which is shown in Fig. 6 and consists of a strap 1 having a buckle 2 at one end so that it may be secured about the wrist of a traffic policeman, as shown in Fig. 1. Strips 3 and 4 extend from the strap 1 in diverging relation to each other and at their free ends carry cross strips 6 which project from opposite sides of the main strips. The strap also carries a shorter strip 7 which is disposed intermediate the width of the palm of a hand adjacent the base of the thumb when the strap is secured about the wrist. If desired, the strap may have a portion adapted to carry a wrist watch 8 which will be preferably located between the attached ends of the strips 3 and 4 and mount the wrist watch against the outer portion of the wrist when the device is in use. The strap also carries a switch consisting of companion sections 9 and 10, one of which is secured to the strap and carries terminals 11 for engagement by conductor wires 12 and the other of which carries terminal blades 13 for engagement by conductor wires 14. By referring to Fig. 7, it will be seen that the two sections 9 and 10 of the switch constitute companion sections of a case which are releasably held together by the companion terminals 11 and 13 and are formed with inwardly extending flanges

15 which contact and serve to retain the section 10 in proper engagement with the section 9. It will thus be seen that the section 10 may be easily and quickly engaged with the section 9 in order to connect the conductor

wires 14 with the conductor wires 12 but may be very easily disconnected when it is desired to prevent current from passing through the wires 14.

The battery 16 which supplies current is carried in a metal case 17 which is curved transversely, as shown in Fig. 5, so that it may be placed in a pocket and this case is provided with a cover 18 which is also formed of metal and releasably held shut by a snap fastener 19. An opening 20 is formed in the cover to receive a plug 21 to which the conductor wires 12 are attached and against the inner face of the cover is secured a contact strip 22 for engagement by the terminal pin 23 of the plug 21. It should be noted that the plug is fitted into the opening, as shown in Fig. 5, with the pins spaced from each other transversely of the cover so that when the cover is closed the second terminal pin 24 of the plug may have engagement with the contact strip 25 of the battery. Therefore, a circuit will be completed through the battery when the section 10 of the switch is engaged with the section 9 and the bulb 26 mounted in the socket 27 will be illuminated. The socket 27 is formed of insulated material and is provided with a base plate 28 which is firmly secured against the inner face of the closure 29 of the stop signal 30, and this base carries terminal strips 28' to which the wires 14 are attached. It should also be noted that a branch wire 31 leads from the wire 14 into the casing of the Go signal 32 and is attached to a similar socket so that both of the signals will be illuminated when the device is in use. It is then only necessary for the traffic officer to hold his hand with either the palm or the back towards a driver in order to indicate to that particular driver whether he wishes him to stop or cross a street intersection.

Each of the signals consists of a casing 33 which may be formed of sheet metal or any other desired material and has one end closed by the closure or door 29 which is hinged to the annular wall of the casing by a hinge 34 and at its opposite side carries a keeper 35 adapted to engage a latch 36. The latch 36 is secured against the inner face of the wall of the casing and provided with an actuating pin 37 which projects through the wall so that the latch may be moved inwardly out of engagement with the keeper and permit the casing to be swung away from the closure or the closure to be swung away from the casing. Eyes 38 extend from opposite sides of the closure for each casing and the ends of the cross strips 5 and 6 are passed through these eyes and folded back upon themselves and secured. The closure for the casing of the stop signal also carries an eye 39 which extends downwardly therefrom immediately over the eyes 38 and is engaged by the upper end of the strip 7. It will thus be seen that the two signals will be securely engaged with

the strips of the carrier and held in proper place against the palm and back of the hand when the device is in use. A clip 40 formed of resilient metal is carried by the closure and is intended to carry a spare bulb 41 to be substituted for the bulb 26 in case the bulb should burn out while the device is in use. The other end of the casing carries a head 42 which may be formed of glass, celluloid or any other transparent or semi-transparent material, and this head is colored so that when the signal is in use colored lights will be displayed. It is preferred to have the head 42 of the signal 30 colored red and the corresponding head of the signal 32 colored green as these are the colors ordinarily used in traffic signals to indicate "Stop" and "Go". In order to retain the head in place, there have been provided rings 43 and 44 which are secured in the casing with the head disposed between them. It should be further noted that the ring or circular band 43 projects from the casing, as shown in Fig. 4, for engagement by the flange 45 of a hood 46. The hood 46 is also preferably formed of celluloid, although any translucent or semi-transparent material may be employed. A legend 47 which may consist of the word "Stop" or the word "Go" is disposed in front of the head 42 and is carried by a shaft 48 which passes through a bearing 49 mounted at the center of the head, and from the inner end of the shaft 48 extends a depending pendulum arm 50 carrying a counter-weight 51 at its lower end. It will thus be seen that the counter-weight arm will serve to rotate the shaft in the bearing 49 when the hand is moved and will at all times retain the legend in such position that it may be easily read by the driver of an automobile. A guide strip 52 which is arcuate in shape fits against the inner edge face of the ring 44 and has its ends secured to blocks 53 which are mounted in the casing, as shown in Figs. 2 and 4. It will thus be seen that the guide strip and its end blocks will serve to limit swinging of the pendulum arm and also prevent it from moving out of proper relation to the head.

When the device is in use, the battery is placed in a pocket and the carrier secured upon the hand with the "Stop" signal 30 against the palm of the hand and the "Go" signal 32 against the back of the hand. The section 10 of the switch is engaged with the section 9 and this will complete a circuit through the battery so that the bulbs of the two signals will be illuminated. When an automobile approaches a street intersection, the driver will signal to the traffic officer the direction in which he wishes to proceed and the traffic officer can turn his hand so that either the "Go" or the "Stop" signal will be displayed to the driver of the automobile and thereby accurately indicate whether he wishes the

driver to stop or proceed in the desired direction. Any desired method of hand signaling which may be easily learned by the drivers of automobiles may be employed to indicate to the traffic officer the direction in which the driver desires to proceed. It will be obvious that, if desired, one of the improved signals may be worn upon each hand and current for them supplied by separate batteries or by a single battery.

Having thus described the invention, I claim:

1. A hand signal comprising a casing, a transparency carried by said casing, a shaft journaled through said transparency, an indicator carried by the outer end of said shaft, an arm depending from the inner end of said shaft, a weight carried by said arm, an arcuate strip in said casing to guide swinging movement of the arm and having abutments at its ends to secure the strip and engages the weight to limit movement of the arm across the transparency, a hood of translucent material covering said indicator and the outer face of said transparency, and means for illuminating the interior of said casing.

2. A hand signal comprising a casing open at one end, a transparency in said casing, having a marginal flange secured against walls of the casing, a band in said casing secured against the walls thereof with its inner edge bearing against said transparency and its outer portion projecting from the casing indicating means pivotally connected with said transparency and spaced from its outer face, a counter-weight yieldably resisting pivotal movement of said indicating means and retaining the same in position to be read, a hood of translucent material for the open end of said casing shielding said indicating means and transparency, and having a marginal flange engaged about the extended outer portion of said band to retain the hood in place and means to illuminate the interior of said casing.

In testimony whereof I affix my signature.
CLIFFORD J. CHAMBERLAND. [L. s.]
